W. E. WINE

CAR DOOR LOCKING DEVICE

Filed Jan. 10, 1922

Fig. 2.

Fig. 1.

Inventor

William E. Wine
Parker Cook

By

Attorney

UNITED STATES PATENT OFFICE.

WILLIAM E. WINE, OF TOLEDO, OHIO.

CAR-DOOR-LOCKING DEVICE.

Application filed January 10, 1922. Serial No. 528,248.

To all whom it may concern:

Be it known that I, WILLIAM E. WINE, a citizen of the United States of America, residing at Toledo, in the county of Lucas and State of Ohio, have invented certain new and useful Improvements in Car-Door-Locking Devices, of which the following is a specification.

My invention relates to new and useful improvements in car door locking devices and especially to a locking device that is designed to be used on cars having drop bottom doors.

One of the objects of the present invention is to provide a locking device which is extremely simple in operation, readily assembled and relatively cheap to manufacture.

Another object of the invention is to provide a locking device comprising a pivotal hook designed to be fastened to the car body for supporting the door, the hook preferably engaging a ledge provided on the door. The ledge may conveniently be an angle iron secured to the bottom of the door, but any other suitable form of means extending beyond the door may be used. To securely hold the hook in supporting engagement with the door I preferably employ a pivoted arm one end of which is capable of being swung into engagement with the hook. The arm is adapted to be held in its locking position by a dog or cam which is so mounted that it will contact with the arm adjacent its pivot and thereby prevent the rotation of said arm until the dog is released.

Still another object of the invention is to provide a locking device of very compact form and preferably furnished with a sheath or housing for the hook which will protect and hold the same against transverse movements.

With these and other objects in view, the invention consists in certain new and novel arrangements and combination of parts as will hereinafter be more fully described and pointed out in the claims.

Referring now to the drawings showing a preferred embodiment of the invention,

Fig. 1 is a sectional view taken on line 1-1 of Fig. 2, showing the locking device and a fragmentary portion of a car door and car body.

Fig. 2 is a side elevation showing the locking device, a fragmentary portion of the car and door, and the dotted lines show-

ing the arm and dog swung to their unlocked position.

Referring now in detail to the invention, the numeral 1 designates a fragmentary portion of a car body to which is pivotally connected a drop door 2. An angle iron 3 is secured to the door 2 and extends beyond the free edge of the latter to afford a ledge adapted to be engaged by the hook of the locking device now to be described.

This locking device may advantageously comprise a bracket or base 4 provided with a plate forming a housing 5 within which a hook 6 is pivotally supported by means of the bolt 7. The lower end of the housing or plate 5 is adapted to form a stop to limit the swing of the locking device, hereinafter to be described, which holds the hook in locked position. The lower portion 8 of the housing is flared to allow for the swinging movement of the hook. The plate 5 is also preferably formed integral with the bracket 4 and may be strengthened by a rib 9 or by a plurality thereof if found necessary or desired. Located to the rear of the hook 6 is an arm 10 which, at a point intermediate its ends, is pivotally connected to said bracket 4 as at 11, so that lever arms of different lengths are provided on opposite sides of said pivot. Above the arm 10 and preferably pivotally connected to said bracket in any suitable manner, is a cam or dog 12 which, when rotated in a counter-clockwise direction, will engage the shorter lever arm of the member 10 and rotate the latter in a clockwise direction until its longer arm is brought into engagement with the lower portion or edge of the housing 5. In this position the end of the longer arm of the member 10 will engage the rear face of the hook 6 and securely hold the latter in engagement with the supporting ledge 3 of the door, as clearly shown in Fig. 2.

A strap 13 may be and preferably is provided for guiding the arm 10 and the dog 12 and to securely maintain the same against lateral movement on the bracket 4. The said bracket is preferably connected to the side of the car body by a plurality of rivets, and a plate 14 may, if desired, be placed on the inside of the car to prevent the bracket from tearing away, the said rivets being extended through said plate 14, as shown. Some of said rivets may be utilized as bearings for the arm 10 and the dog 12, if desired.

The hook and bracket, as well as the arm and dog, may be cored for lightness, if desired.

I have shown only one locking device, and 5 one side of a door, but it is to be understood that a similar locking device will be applied to the other side of the door so that both corners will be rigidly supported and locked in position.

10 From the foregoing it will be seen that I have provided a locking device which will securely hold the door in its closed and locked position until the dog is released by hand so as to permit the longer lever arm 15 of the member 10 to swing downwardly by gravity to released position. The locking device which is exceedingly simple in construction, easily assembled, readily and quickly operable and relatively cheap to 20 manufacture.

Many slight changes might be made without in any way departing from the spirit and scope of the invention.

Having thus described my invention, 25 what I claim as new and desire to secure by Letters Patent is:

1. A door locking device comprising a base, a hook pivotally mounted on said base, an arm pivotally mounted on said base, and 30 positioned to the rear of the hook and arranged to swing by gravity normally away from said hook, said arm contacting and holding said hook in its foremost position when said arm is in a locking position and 35 means for retaining said arm in its locked position.

2. A locking device for doors comprising a base, a hook pivotally mounted on said base, a pivotally mounted arm positioned to 40 the rear of the hook and adapted to hold said hook in its foremost position when said arm is swung against said hook, and means contacting with the outer end of said arm to hold said arm and said hook in their 45 locked position.

3. A locking device for doors comprising a bracket, a housing on said bracket, a hook pivotally mounted in the upper end of said housing, an arm pivotally mounted between 50 its ends behind said hook and contacting with said hook when swung to a locked position, a dog pivotally mounted on said bracket above the rear end of said arm to hold said arm in position for preventing 55 disengagement of said hook and door when said arm is in locking position.

4. A locking device for doors comprising a bracket, a flared housing integral with said bracket, a hook pivotally mounted in the 60 upper end of said housing, an arm pivotally mounted intermediate of its ends on said bracket and to the rear of said hook, said arm retaining said hook in its locked position when the end of said arm adjacent said 65 hook is in its upper position, and means for

maintaining the opposite end of said arm against pivotal movement to thereby hold the arm in its locking position.

5. In combination with a freight car, a door, a ledge on said door extending beyond the side thereof, a bracket secured above said ledge, a hook in said bracket engaging with said ledge on said door when the door is in its closed position, an arm pivoted to the bracket to the rear of said hook, and contacting with said hook when said arm is swung to a locking position, and means pivoted above said arm and adapted to engage therewith to hold said arm against rotation. 70

6. A locking device for doors comprising a bracket, a housing on said bracket, a hook pivotally mounted in the upper end of said housing, and an arm pivotally mounted behind said hook and contacting therewith when swung into a locked position, the said 80 arm being adapted also to contact a portion of said housing, the latter forming a stop or limit for the upward movement of said arm. 85

7. A locking device for doors comprising a bracket, a housing on said bracket, a hook pivotally mounted in said housing, an arm pivotally mounted behind said hook and contacting with said hook when rotated to a locked position, said housing forming a stop for limiting the movement of said arm, and 90 means for retaining the arm in its locked relation to said hook.

8. A locking device for doors comprising a bracket, a housing on said bracket, a hook pivotally mounted in the upper end of said housing, an arm pivotally mounted between its ends behind said hook and contacting with said hook when swung to a locked position, said arm also contacting the lower edge of said housing when swung to its locked position whereby said housing forms a stop for said arm, and means for holding the said arm in contact with said housing. 100 105

9. A locking device for doors comprising a bracket, a housing on said bracket, a hook pivotally mounted in the upper end of said housing, and locking means pivotally mounted behind said hook, said housing providing a stop for limiting the movement of said locking means. 110 115

10. A locking device for car doors involving a pivoted hook, means carried by the car door for cooperating with said hook to support the door in closed position, rotatable means adapted to engage said hook to maintain the latter in door supporting position, a stop for limiting the rotation of said rotatable means in one direction, and releasable means cooperating with said rotatable means to limit movement of the latter in the opposite direction. 120 125

11. A locking device for car doors involving a pivoted hook, means carried by the car door for cooperating with said hook to support the door in closed position, rota- 130

table means for preventing said hook from assuming a position allowing said door to open, and a plurality of stops for limiting the movement of said rotatable means, one of said stops being adapted to limit the rotation of said last named means in one direction, and the other of said stops serving to limit the rotation of said rotatable means in the opposite direction, said last named stop being releasable to permit said rotatable means to move away from said other stop.

12. A locking device for car doors involving a pivoted hook, means carried by the car door for cooperating with said hook to support the door in closed position, means movable with respect to said hook for engaging the latter and preventing it from executing a door releasing movement, said last named means being adapted under the influence of gravity to assume a position permitting said hook to swing to door releasing position, and releasable means for maintaining said movable means in locked relation to said hook.

13. A locking device for car doors involving a pivoted hook, means carried by the

car door for cooperating with said hook to support the door in closed position, means movable into the path of releasing movement of said hook and adapted to engage the latter for preventing said hook from executing a door releasing movement, and means for maintaining said last named means in hook engaging position, said movable means being disengageable from said hook to permit the latter to assume a door releasing position.

14. A locking device for car doors, involving a bracket secured to the car side, a hook pivotally mounted on said bracket, means carried by the car door for cooperating with said hook to support the door, a device pivoted on said bracket and adapted to move into engagement with said hook to prevent the latter from executing a door releasing movement, and a means pivoted on said bracket for engaging said pivoted device to maintain it in locked relation to said hook, the pivotal axes of said hook, pivoted device and pivoted means being in spaced relation.

In testimony whereof I affix my signature.

WILLIAM E. WINE.
